(57) **CLAIM**

The ornamental design for a vegetable tray as shown and described.

DESCRIPTION

FIG. 1 of the drawings is a top, front, side perspective view of the vegetable tray showing, in particular, the ornamental design thereof;

FIG. 2 of the drawings is a bottom, back, side perspective view thereof;

FIG. 3 of the drawings is a front elevation view thereof;

FIG. 4 of the drawings is a back elevation view thereof;

FIG. 5 of the drawings is a first side elevation view thereof;

FIG. 6 of the drawings is a second side elevation view thereof;

FIG. 7 of the drawings is a top plan view thereof;

FIG. 8 of the drawings is a bottom plan view thereof;

FIG. 9 of the drawings is a top, front, side perspective view thereof, wherein the lid of the vegetable tray is removed;

FIG. 10 of the drawings is a bottom, back, side perspective view thereof, wherein the lid of the vegetable tray is removed;

FIG. 11 of the drawings is a front elevation view thereof, wherein the lid of the vegetable tray is removed;

FIG. 12 of the drawings is a back elevation view thereof, wherein the lid of the vegetable tray is removed;

FIG. 13 of the drawings is a first side elevation view thereof, wherein the lid of the vegetable tray is removed;

FIG. 14 of the drawings is a second side elevation view thereof, wherein the lid of the vegetable tray is removed;

FIG. 15 of the drawings is a top plan view thereof, wherein the lid of the vegetable tray is removed; and,

FIG. 16 of the drawings is a bottom plan view thereof, wherein the lid of the vegetable tray is removed.
